UNITED STATES PATENT OFFICE.

CECIL VILHELM SCHOU, OF COPENHAGEN, DENMARK.

PROJECTILE.

SPECIFICATION forming part of Letters Patent No. 734,966, dated July 28, 1903.

Application filed January 17, 1903. Serial No. 139,475. (No model.)

To all whom it may concern:

Be it known that I, CECIL VILHELM SCHOU, a subject of the King of Denmark, residing at Copenhagen, Denmark, have invented certain new and useful Improvements in Projectiles, of which the following is a full, clear, and exact description.

This invention relates to projectiles or bullets provided with material adapted to develop smoke or light, or both, when they come in contact with the target or any other obstruction in their path.

The object of the invention is to enable the gunner to determine the range, this being possible by reason of the fact that the smoke or flash created at the impact of the projectile shows whether it falls short or overreaches the mark and to what extent.

In another application filed by me, Serial No. 123,120 $\frac{1}{2}$, I have described and claimed a material capable of generating a dense smoke and suitable more particularly for schrapuels and shells. The present invention, however, is more especially adapted for bullets and other small-caliber solid projectiles generally used in hand-firearms, by the aid of which a soldier can ascertain the distance of the enemy by firing one or more of the prepared bullets before firing the ordinary bullets.

My present invention consists in general of a bullet or other projectile having attached thereto, preferably at its forward end, a fragile capsule containing material adapted to burn when exposed to the atmosphere and develop smoke or light, or both.

My invention is illustrated in the accompanying drawings, in which—

Figure 1 is a sectional view of a bullet equipped in accordance with my invention. Fig. 2 is a similar view showing a modification. Fig. 3 is also a sectional view showing means for protecting the capsule against fracture from the shock of discharge, and Figs. 4 and 5 illustrate further modifications.

The bullet or projectile itself may consist of the usual body *a*, of lead or other material, and may have the usual conical formation at the forward end.

b indicates a capsule which I may apply to the forward end of the bullet in any exposed manner, so that it will be shattered when the

bullet strikes a reasonably hard object. This capsule may be made of thin sheet metal or glass and inserted into an orifice adapted to receive it in the body of the bullet and with one end projecting to make contact with the object struck. The capsule contains a quantity of any substance adapted to become inflamed when exposed to the atmosphere—such, for instance, as zinc-ethyl, the combustion of which produces a flash of light and a dense smoke visible a long distance. The capsule may be held in place when necessary by a sheath *c* of sheet metal, in which the projectile may be incased and which may have an opening at its forward end, through which the point of the capsule will project.

In the formation shown in Fig. 2 the special casing for the capsule is omitted, the inflammable material being placed directly in a chamber *e*, formed partially by a cavity in the forward end of the projectile and partially by the sheath *c*, which covers the cavity and is of sufficiently fragile construction to give way when the projectile strikes and expose the inflammable material to the atmosphere. Such a chamber for the inflammable material is preferably filled by means of a passage *e'*, leading rearward through a projectile, which after the filling operation is closed by a suitable plug *e''*.

Fig. 3 shows a method of sustaining a capsule when it is made of specially fragile material, such as glass, which needs protection against the shock imparted to it when discharged from the gun. In this instance the cavity in the bullet which receives the capsule is lined with a soft cushioning material *f*, such as soft rubber or a mixture of glycerin and glue.

Fig. 4 illustrates a means for exposing the inflammable material when the projectile strikes without necessarily fracturing the container. This consists in making the container or capsule in the form of a cup *g*, which is inverted and fixed tightly over the forward end of the projectile, the latter having a slight depression, if desired, which is inclosed by the cup and in which is placed a fulminate cap *g'*. The cup *g* carries a needle or firing-pin *g''*, which is driven against the fulminate when the projectile strikes, causing a slight

explosion, which drives off the cup, exposes the contents to the atmosphere, and fires the same.

Fig. 5 shows a construction which differs 5 slightly from Fig. 4 in that the inverted cup contains a fragile sealed glass tube *h*, containing the liquid zinc-ethyl. The fracture of this tube exposes its contents to the atmosphere and, becoming inflamed, sets fire to the surrounding material, which, though not being capable of spontaneous combustion, will develop a great quantity of smoke when fired, a serviceable material for this purpose being flowers of sulfur and sublimated zinc.

5 It is obvious that the usual shape of the projectile may remain intact and that the capsule may be given a suitable shape to fit thereon, thus avoiding any cavity in the body of the projectile, which might cause it to split 5 at the impact.

When any of these types of projectile are fired from a gun, the smoke developed at the impact will clearly show to the gunner where the projectile strikes and he can adjust the 5 sights of the gun accordingly. If the firing is done at night, the flash which also occurs at the impact gives the same information.

Having described my invention, I claim—

1. A projectile or bullet for firearms in combination with a fragile capsule containing a smoke-developing material and carried in or upon the projectile or bullet.

2. A projectile or bullet for firearms in combination with a fragile capsule containing a material capable of developing smoke when exposed to the atmosphere and attached to the projectile or bullet. 35

3. A projectile or bullet provided at its forward end with a chamber in combination with a capsule of fragile material containing a substance adapted to become inflamed when exposed to the atmosphere, said capsule being located in said chamber and exposed at the forward end of the projectile. 40

4. A projectile or bullet having at its forward end a chamber or cavity lined with a cushioning material, in combination with a capsule of fragile material located in said chamber and containing material capable of developing smoke when exposed to the atmosphere. 45

5. The combination with a projectile or bullet provided with a chamber containing material adapted to generate a smoke when exposed to the atmosphere and means for exposing said material at the impact of the projectile. 50

In witness whereof I subscribe my signature in presence of two witnesses.

CECIL VILHELM SCHOU.
